US0D1008881S

(12) **United States Design Patent** (10) Patent No.: **US D1,008,881 S**
 (45) Date of Patent: ** Dec. 26, 2023

(54) **BICYCLE FRAME**

(71) Applicants: **GALAXY BICYCLE CO., LTD.**,
 Heshan (CN); **RALLY**
(GUANGZHOU) EBIKE CO., LTD.,
 Guangzhou (CN)

(72) Inventor: **Zijie Yang**, Anlu (CN)

(73) Assignee: **GALAXY BICYCLE CO., LTD.**,
 Heshan (CN)

(**) Term: **15 Years**

(21) Appl. No.: **29/824,241**

(22) Filed: **Jan. 24, 2022**

(51) LOC (14) Cl. **12-11**

(52) U.S. Cl.

USPC **D12/111**

(57) **CLAIM**

The ornamental design for a bicycle frame, as shown and described.

DESCRIPTION

FIG. 1 is a perspective view of a bicycle frame showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
